COMPRESSOR LOAD PROTECTOR

Clyde E. Floeger, Evansville, Ind., assignor to
 Servel, Inc., New York, N. Y., a corporation of
 Delaware

Application September 7, 1946, Serial No. 695,482

4 Claims. (CL 230—24)

1

This invention relates to load protectors for electric motors, and particularly to protectors for electric motors used for driving the compressor of a refrigerating system of the compressor-condenser-expander type.

In my prior Patent No. 2,043,058, granted June 2, 1936, I disclose a magnetic unloader to relieve an electric motor of its load at starting and to keep the load relieved until the motor has attained the requisite speed. This prior unloader, which is operated by the leakage magnetic field of the motor, and which opens an unloading valve at starting and closes the unloading valve when the leakage field decreases, operates very satisfactorily as far as it goes. However, my prior invention protects the electric motor against starting loads only. That is, the unloading valve is either fully open or fully closed depending upon whether the motor is just starting or whether it has attained the requisite speed.

The present invention contemplates a device for protecting electric motors against running loads as well as against starting loads. So far as I am aware, compressor unloading devices have not been controlled directly by the flux current of the motor for governing the running load.

Specifically, my motor protector comprises a valve in the suction line between the expander and the compressor of a refrigerating system. This valve is conveniently positioned within the motor-compressor housing of an hermetically sealed unit and includes a member constructed of magnetic material so positioned and arranged with respect to the motor that it is attracted by the leakage magnetic field to close the valve at starting, which valve is opened as by springs as the leakage field decreases as the motor comes up to speed. The valve is so positioned relative to the motor stator and rotor that it floats back and forth depending upon the intensity of the magnetic leakage field. At starting, the leakage field is of maximum intensity and the valve is drawn to closed position. Then, as the rotor approaches running speed and the leakage field decreases, the springs gradually open the valve admitting refrigerant vapor to the compressor. Then, with the motor running normally, the valve remains open. If, however, the motor is suddenly overloaded as by an overload applied to the compressor the valve is drawn to closed or partly closed position depending upon the load. In other words, the valve is in fully open position only so long as a normal load is applied to the compressor and the rotor is operating substantially at full speed.

2

The use of my improved unloader enables a motor compressor unit to be more heavily loaded in that the running load and the displacement of the compressor can be balanced at the design or operating point. Heretofore the displacement has had to be adjusted lower so that the maximum overload or pull-down conditions will not be beyond the capacity of the motor.

This invention will be more fully understood by reference to the following description taken in connection with the accompanying drawing wherein:

Fig. 1 is a view partly in section of the motor end of a motor-compressor unit incorporating my invention;

Fig. 2 is a view similar to Fig. 1 but showing my improved unloader valve in full open position;

Fig. 3 is a transverse sectional view taken on line 3—3 of Fig. 1.

Referring to the drawing, an hermetically sealed casing 10 encloses a motor-compressor unit of a refrigerating system. The particular type of compressor that is employed in the refrigerating system forms no part of this invention, therefore only the motor end of motor-compressor unit is illustrated. As shown, an electric induction motor comprising a stator 12 and rotor 13 having an air gap 14 therebetween is arranged within the casing. The stator may be secured within the casing in any suitable manner as by a shrink fit. The casing is provided with a removable head 16 upon which is mounted my improved motor protector designed generally by reference numeral 18.

This motor protector includes an annular mounting plate 20 hermetically secured to the head of the casing as by screws 22 and having a cylindrical valve cup 24 hermetically secured thereto. An annular flux ring 26 made of magnetic material is mounted for axial sliding movement upon the cup 24 and together with the cup forms a valve for controlling the flow of refrigerant vapor through an opening 28 in the head of the casing, which opening is connected by a suitable conduit, not shown, to the suction side of the expander of the refrigerating system. Inward movement of the flux ring is limited by a stop plate 30 secured to the valve cup by screws 32. Four equally spaced guide bolts 34 provided with compression springs 36 are mounted between the mounting plate 20 and the stop plate 30. In order that a universal unloader may be used for different size motor-compressor units, suitable means, not shown, may be provided for

adjusting the springs 36. As shown, the flux ring is provided with a cylindrical sleeve 28a which fits snugly upon the valve cup 24 for axial movement relative thereto. This sleeve is provided with a plurality of ports 38 which cooperate with a like plurality of ports 40 in the valve cup for admitting refrigerant vapor to the compressor. A fine mesh strainer 42 is mounted in the valve cup.

In operation, as above described, the magnetic field of the motor is greatly distorted at the instant of starting and consequently the magnetic ring 26, the inner end of which is positioned adjacent the rotor of the motor, is attracted and moved to the right from the position shown in Fig. 2 to that shown in Fig. 1, thereby moving the valve ports 38 and 40 out of register and closing the valve, thus taking the load off the compressor. The magnetic ring will remain in this attracted position until such time as the rotor picks up speed and the leakage flux has decreased to the extent that the force of the compression springs is sufficient to gradually move the magnetic ring to the left bringing the valve ports into register, whereby refrigerant vapor is drawn from the suction line through the opening 28, through the ports 40 and 38 and through the gap between the motor stator and rotor and into the compressor, not shown, thus the compressor is gradually loaded. As the rotor comes up to speed the current in the motor windings decreases and the leakage field diminishes whereby the springs draw the magnetic ring to the position shown in Fig. 2 with the valve in fully open position and the compressor fully loaded. The valve remains in the open position shown in Fig. 2 so long as the motor-compressor unit operates normally. If, however, an abnormal load is applied to the unit, as by a sudden overload on the expander of the refrigerating system, which overload is applied to the compressor and from there to the motor, a magnetic field leakage is created which attracts the magnetic ring, thus partly closing the valve and reducing the load on the compressor. In this manner the magnetic ring floats back and forth opening and closing the valve to a greater or less degree in accordance with the load placed upon the motor.

Although but one specific form of my invention has been illustrated and described and this specific form has been incorporated in a motor-compressor unit of a refrigerating system of the compressor-condenser-expander type, my invention obviously may take other forms and be variously applied. The invention is therefore limited only as defined in the claims.

Having thus described my invention, I claim:

1. In combination a compressor, an electric motor for operating said compressor, a valve connected to said compressor for varying the load thereon, said valve being provided with a member constructed of magnetic material disposed within the magnetic leakage field of said motor to be attracted thereby for moving said valve in one direction, means opposing the attraction of the magnetic leakage field urging said valve in the opposite direction, the construction and arrangement being such that when the magnetic leakage field is of maximum intensity, as at the instant of starting the motor, the valve is moved in one direction to unload the compressor and as the motor approaches running speed the valve is moved in the opposite direction to load the compressor, thereafter during operation of the compressor the valve modulates between open

and closed positions in accordance with the intensity of the magnetic field as reflected by the load on the compressor.

2. In combination a compressor, an electric motor for operating said compressor, an unloading valve in the suction side of said compressor, said valve being provided with a member constructed of magnetic material disposed within the magnetic leakage field of said motor to be attracted thereby for closing said valve, means opposing the attraction of the magnetic leakage field urging said valve toward open position, the construction and arrangement being such that when the magnetic leakage field is of maximum intensity, as at the instant of starting the motor, the valve is closed and as the motor approaches running speed the valve is urged toward open position, thereafter during operation of the compressor the valve modulates between open and closed positions in accordance with the intensity of the magnetic field as reflected by the load on the compressor.
3. In combination an electric motor, a compressor operatively connected to the motor in such manner as to place a load upon the motor thereby causing a magnetic leakage field of varying intensity to be set up in the motor, means utilizing the intensity of the magnetic leakage field for governing the load placed upon the motor, said means including a valve connected to the compressor, said valve having a portion thereof disposed within the magnetic leakage field to be attracted thereby for moving the valve in one direction, means opposing the attraction of the magnetic leakage field urging the valve in an opposite direction, the construction and arrangement being such that when the motor is running and the load on the compressor is increased the valve is moved in one direction thereby decreasing the load on the motor and as the motor approaches running speed the valve is gradually moved in an opposite direction increasing the load on the motor.

4. In combination an electric motor, a compressor operatively connected to the motor in such manner as to place a load upon the motor thereby causing a magnetic leakage field of varying intensity to be set up in the motor, means utilizing the intensity of the magnetic leakage field for governing the load placed upon the motor, said means including a valve in the suction side of the compressor, said valve having a portion thereof disposed within the magnetic leakage field to be attracted thereby for moving the valve toward closed position, means opposing the attraction of the magnetic leakage field urging the valve toward open position, the construction and arrangement being such that when the motor is running and the load on the compressor is increased the valve is partly closed thereby decreasing the load on the motor and as the motor approaches running speed the valve is gradually opened.
